BUTTON SETTING MACHINE.

No. 394,231.

Patented Dec. 11, 1888.

UNITED STATES PATENT OFFICE.

JOHN H. VINTON, OF BOSTON, MASSACHUSETTS, ASSIGNOR TO THE PENINSULAR NOVELTY COMPANY, OF GRAND RAPIDS, MICHIGAN.

BUTTON-SETTING MACHINE.

SPECIFICATION forming part of Letters Patent No. 394,231, dated December 11, 1888.

Application filed April 24, 1888. Serial No. 271,683. (No model.)

To all whom it may concern:

Be it known that I, JOHN H. VINTON, of Boston, county of Suffolk, and State of Massachusetts, have invented an Improvement 5 in Button-Setting Machines, of which the following description, in connection with the accompanying drawings, is a specification, like letters on the drawings representing like parts.

10 This invention has for its object to improve button-setting machines in such manner that staple-shaped fastenings may be automatically threaded into the eyes of buttons and be then driven into the material and have their prongs clinched on an anvil.

15 In the machine herein to be described staples placed in a hopper are delivered therefrom upon a raceway, where they meet the eyes of the buttons placed in another hopper and delivered therefrom into a chute, the staples being acted upon one by one by a driver and threaded into the eyes of the buttons, each staple so inserted into the eye of a button being driven by a driver along the 20 raceway, into which the staple is placed when being threaded through the eye of the button, the staple carrying with it to the boot or shoe 25 the button.

30 The buttons, as herein shown, are delivered from the button-chute into a pocket wheel or carrier, which is rotated intermittently, and each button is removed from a pocket of the carrier by a transerrer into position to leave the eyes of the buttons open in the driver-passage, so that as the driver descends a leg of the 35 staple will be threaded into the eye of the button.

35 The transerrer herein shown is a horizontally-reciprocating bar. The driver is of peculiar construction—that is, one side is longer 40 than the other, to thus enable the button-eye to turn a quarter-turn as or just after the staple-leg enters it, for then that part of the button-eye outside the staple has to swing upwardly in the arc of a circle to the central part of the crown, so that the widest part of the button shank or eye may travel in a vertical slot as the staple having the button on it is driven into the material.

45 My invention in button-setting machines 50 consists in a block having a driver-passage

and a staple raceway or bar in communication therewith, combined with a staple-detaining finger located opposite or at the end of the said raceway or bar to support a single 55 staple, and with a driver, substantially as will be described; also, in a staple raceway or bar, a block having a driver-passage slotted at one side, a staple-detaining finger located at one end of the said raceway or bar, and a button 60 chute or raceway, combined with a transferer to transfer the buttons singly into the said slot under the driver to drive a staple into the end of a button-shank, as will be described; also, in a driver-passage slotted at 65 one side for the entrance into it of a shank of a button with its eye uppermost for the reception of one leg of a staple, combined with a foreshortened driver to permit the button-shank to turn a quarter round, substantially 70 as will be described.

Other features of my invention will be pointed out in the claims at the end of this specification.

Figure 1 is a front elevation of a machine 75 embodying my invention, the staple-receiving hopper being partially broken out. Figs. 1^a and 1^b are enlarged details of the driver for threading the staple into the eye of the button and the raceway, the parts being 80 shown in different positions, Fig. 1^a representing the shank of the button when first entered by the leg of the staple, the position Fig. 1^b representing the shank of the button when the staple has been fully threaded 85 thereon. Fig. 2 is a vertical section to the left of the line *a*, Fig. 1; Fig. 2^a, a sectional detail in the line *x*², to show the cam and devices for moving the driver *a*. Fig. 3 is a sectional detail in the line *x*¹, to show the lever 90 and cam for moving the driver-carrier. Fig. 4 is a partial section in the line *x*², to show the staple raceway or bar and the guide or raceway section which receives the staple with button attached and from which the 95 staple is driven. Fig. 5 is a detail in front elevation of the button carrier and transerrer. Fig. 6 is a sectional detail at the left of the line *x*³, Fig. 1. Fig. 7 is a detail of the carrier-wheel and its ratchet. Fig. 8 is an 100 enlarged detail of the front of the guideway in which the shank of the button is placed

by the transferrer, the finger 43 being omitted to better show part of the driver, it being elevated just above the end of the staple raceway or bar. Fig. 9 is a section of Fig. 8 below the dotted line x^5 . Fig. 10 is a detail enlarged, showing the finger 42 and the spring for holding it against the raceway-bar A^{16} . Fig. 11 shows the driver a separately. Fig. 12 is a section on line x^6 , Fig. 4. Fig. 13 shows the lever c^5 detached.

The frame-work A , of suitable shape to sustain the working parts, has suitable bearings for the main shaft A' , provided with several cams and pulleys, the driving-pulley A^2 , as herein shown, being of the class known as "frictional." A stand, A^4 , receives in it a stud, A^5 , on which is mounted loosely the staple-hopper A^6 , into which is thrown in mass the staple-form fastenings s , as shown at Fig. 1. The hopper having within it several radial shelves or lifters, 40, which raise the fasteners and discharge them so that the fasteners drop upon an inclined guide-wire, 41, connected to the upper end of the staple raceway or bar A^{16} , some of the fasteners falling correctly upon the said wire or straddling it and sliding upon the said raceway or bar, it in practice having a suitable cover, as t^2 .

The staple-hopper has attached to it a toothed wheel, A^7 , which is engaged and rotated by a pinion, A^8 , on a short shaft, A^9 , provided with a belt-pulley, A^{10} , over which is passed a belt, A^{12} , driven from the pulley A^{15} on the main shaft, the said belt between the said pulleys running against two bearing-pulleys, A^{13} , on an inclined stud, A^{14} .

The staple-raceway or guide-bar A^{16} has its upper end extended into the staple-hopper, so that the latter in its rotation drops the staples upon the extension 41 to ride down the said raceway, those staples properly lodged thereon sliding down the raceway, the lower end of which terminates (see Figs. 2 and 8) in an opening in a stand, B , erected on the bed of the frame, the endmost staple coming against a pivoted finger, 42, acted upon by a spring, 43, (see Figs. 4 and 10,) which normally keeps the end of the finger against the end of the staple-raceway A^{16} , as shown in the detail, Fig. 4, the lower end of the said finger being inturned, so as to receive upon it (see Fig. 4) the endmost staple of the series of staples straddling the raceway A^{16} , and supporting the said staple in position to be struck by the auxiliary driver a , which acts to thread the staple into the eye of the button-shank when the latter is brought into position with its eye flatwise and open vertically (see Fig. 1^a) in the driver-passage in which the driver a works, the said passage being intersected at right angles, or nearly so, by a slot, 2, into line with which are brought at intervals the shanks of the buttons, the shanks being held in slots 3 of a carrier, c , shown as a wheel having a series of radial slots, the said carrier being at the front end of a shaft, c' , (see Fig. 7,) having its bear-

ings in the stand B , the said shaft at the rear side of the stand having attached to it a ratchet-wheel, c^2 , which is engaged and rotated step by step by a pawl, c^3 , (see Fig. 5,) acted upon by a spring, c^4 , the pawl being pivoted on a pawl-carrier, c^5 , (see also Fig. 13,) having applied to it a link, c^6 , pivoted to a lever, c^7 , having its fulcrum on a horizontal screw-stud, c^8 , in a bracket secured to the bed-plate, the rear end of the said lever having a roll, c^9 , which is acted upon by a cam, c^{10} , on the main shaft, a spring, c^{12} , normally acting to keep the said roll against the said cam. 80

The end of the pawl-carrier c^5 and of the lever c^7 , which are joined by the link c^6 , will in practice be of ball shape, and the link will be shaped to receive the said ball-shaped ends and form a ball-joint connection. 85

The stand B has erected upon it a button-raceway, B' , having a slotted cover-plate, B^2 , held by bars B^3 , the upper end of the raceway terminating in the button-hopper B^4 , it having in it a rotating shaft, B^5 , on which (see Fig. 6) is fastened a wheel, B^6 , having a series of holes, 30, in which enter the buttons, the latter, when they arrive opposite an opening, 4, in the hopper, falling over to the left into the button-raceway, pins B^7 , attached to the wheel B^6 , agitating the buttons. 90

The endmost buttons of the column of buttons in the button-raceway drop one after another into one after another of the radial slots 3 of the button-carrier c , and, as herein shown, by two steps or movements of the carrier are brought with the widest part of their shanks in horizontal position opposite the slot 2 in the side of the driver passage or guideway d at the end of the staple raceway or bar, at which time the transferrer 6 (herein shown as a sliding finger at the end of a bar, d' , free to slide in bearings d^2 of a stand, d^3) is moved forward by the cam d^4 and made to act upon the head of the button and push it horizontally out from the carrier c , the shank of the button entering the slot 2, the transferrer leaving the button-shank standing across the driver-passage in the guide d , with the eye of the button open, as in Fig. 1^a, and in vertical 115 position to be entered by one leg of the staple next to be pushed down by the auxiliary driver a .

The transferrer-bar d' has a stud, 48, (see Fig. 1,) which is embraced by the forked end of a lever, 49, pivoted (see Fig. 2) on a stud or screw at the top of the lug 50 on the bed-plate, the rear end of the said lever having a roller-stud, 51, which is acted upon by the cam d^4 on the shaft A' . 125

The transferrer is pulled back by a spring, 57, (see Fig. 1,) connected to the lever 49 and to a stud, 58. The heads of the buttons between the end of the button-raceway and the slot 2 are acted upon by a retaining-plate, 5, shown as of curved shape, and preferably a spring-plate attached to the stand B by screws, as d^6 . 130

Fig. 1^a on a larger scale shows the face of

the guide in which the staples are placed by the auxiliary driver a , and in said figure it will be seen that the end of the staple-race-way A^{16} terminates just above the slot 2, (see 5 also Fig. 8,) so that the staple acted upon by the driver a may be pushed down below the yielding finger 42 , which supports it at the end of the raceway A^{16} , to enter one leg of the staple into the eye of the button.

10 The corner 44 (see Fig. 1^a) at the junction of the slot 2 with the vertical slot 45, in which descends the shank of the button s' after the staple has been threaded into it, is cut away or rounded so as to permit the button-shank 15 to start and turn one-quarter around, so as to get from the horizontal slot 2 into the vertical slot 45; but this could not be done if both sides of the crown of the staple were acted upon alike by the end of the driver a , for it 20 will be seen that if the part 46 of the driver a extended down as low as the part 47, when the driver acted to push the staple into the eye of the button, then the part 46 would meet the shank of the button and would prevent the 25 rear half of the eye or shank from rising and turning, as is necessary to enable the button-shank to turn from the position Fig. 1^a and stand with the broadest part of its eye in the vertical slot 45, as in Fig. 1^b.

30 To enable the button-shank to turn over from its full-line position, Fig. 1^a, to assume the position Fig. 1^b, to stand in vertical position in the slot 45 of the driver-passage d , that part 46 of the driver a nearest the passage 2 is shorter than the other part, 47, so that the button-eye, as it is first entered by the staple-leg, is so acted upon by the said leg as to cause the eye to follow along the rounded corner 44 with the staple and tip up 35 over on the staple-crown, and in so doing not be interfered with by the driver a . Shortening the effective length of one side or part of the driver for the purpose stated makes what I call a "foreshortened" driver, and, believing myself to be the first to conceive the 40 necessity of so shaping the driver as to permit the button-shank to tip freely from the leg of the staple over upon the crown of the staple in line with the center of the driver, I 45 do not desire to limit my invention to the exact form of driver shown, but deem as within the scope of my invention any equivalent construction of driver which is made to permit a free quarter-rotation of the shank of the 50 button under the driver.

55 The sectional view, Fig. 9, shows the shape of the groove 45 of the guideway d , in which the driver a and staple travel. The guideway d is shown as quite short; but just below it is placed a holding-guide, g , having the same 60 cross-section as the guideway d , the holding-guide g having a shouldered back, (see Fig. 12,) to enter a correspondingly-shaped groove in the end of a slide-bar, g' , fitted to slide 65 transversely in the stand B, the bar having a roller or other stud, g^2 , which is acted upon by the cam g^3 on the shaft A' , the roller be-

ing kept against the cam by a spring, g^4 , while the guide g is normally kept up by a spring, g^5 . The holder-guide has a pin or stud, as 56, 70 to arrest the staple and button until removed therefrom by the driver h , which enters the driver-passage h' in the holder-guide g , and drives the fastener therefrom into the material of a boot, shoe, or other article laid upon 75 the anvil h^2 , supported on the beak h^3 , the said anvil h^2 having usual pockets to clinch the legs of the staple inwardly and turn the points of the staple-legs up into or against the stock, as in United States Patents Nos. 80 324,053 and 312,987.

The driver h is fixed by screws 10 (see Fig. 1^a) to a vertically-reciprocating frame, m , having behind the driver a guideway or groove for the reception of a presser bar or slide, 12, having a stem, 13, extended upwardly between a friction clamp or driver, 14, supported at the top of the frame m , the upper end of the stem 13, at each ascent of the said frame, meeting a stop, 15, attached to the stand B, and arresting the upward movement of the presser 85 12 before the driver-frame m and driver arrive at their upstroke, thus leaving the presser, when the driver is fully elevated, with its end 90 nearly at the end of the presser, as in Fig. 4. 95

The driver-frame has a grooved shank, m^3 , which is made to slide upon a guide-stand, m^4 , secured to the bed-plate, the shank and stand being each properly dovetailed together, so as to slide one on the other. The 100 shank m^3 has, as shown, a stud, m^5 , which is engaged by a driver-actuating lever, m^6 , pivoted on a stud, m^7 , of a lug, m^8 , the lever having at its end (see Fig. 3) a roll which is 105 acted upon by a cam, m^9 , on the shaft A' , a spring, m^{10} , keeping the roll against the said cam.

As the driver-frame and driver are depressed to drive a fastener into the material, the driver enters the driver-passage h' and bears against 110 the crown of the staple, and the presser 12 meets the holder-guide g and causes it to descend upon the material between the said holder-guide and the anvil, and as the material is so clamped the holder-guide and presser 115 come to rest; but the driver-frame m and driver continue to descend until the driver h drives the staple which is threaded into the eye of the button, into the material, and from 120 the driver-passage h' , the friction clamp or device at such time sliding down upon the shank 13.

The driver a is attached by screws n to a slide or driver head, n' , made vertically movable in a groove at the side of the stand B, the 125 said slide or head n' having at one side next the guide-stand m^4 a stud or projection, n^3 , on which is a link, n^4 , which is pivoted at n^5 to the end of a lever, n^6 , pivoted at n^7 , (see Fig. 2^a,) the rear end of the said lever being acted 130 upon by a cam, n^8 , on the shaft A' to cause the descent of the driver a , the opposite movement of the lever n^6 being produced, as herein shown, by a spring, n^{10} .

A detent, r , acted upon by a spring, r' , (see Fig. 5,) acts to prevent any retrograde movement of the carrier c .

I claim—

- 5 1. In a button-setting machine, the block having the driver-passage and the staple raceway or bar in communication therewith, combined with the staple-detaining finger located opposite or at the end of the said raceway or 10 bar to support a single staple, and with a driver, substantially as described.
2. The staple raceway or bar, the block having the driver-passage and slotted at 2, and a button chute or raceway, combined with a 15 transerrer to transfer the buttons singly into the slot 2 and with a driver to drive the staple into the eye of the button-shank, substantially as described.
3. The staple raceway or bar, the block having the driver-passage and slotted at 2, and the staple-detaining finger located at the end of the staple raceway or bar, and a button chute or raceway, combined with a transerrer to transfer the buttons singly into the slot 2 25 and with a driver to drive the staple into the eye of the button-shank, substantially as described.
4. The block having the driver-passage 45 and slotted at 2 for the entrance into the driver-passage of the shank of the button, with its eye opened for the reception of one leg of a staple, combined with a foreshortened driver to permit the button-shank to turn one- 30

quarter around while traveling from the slot 2 into the driver-passage, one part of the shank 35 of the button curving upwardly about the crown of the staple, substantially as described.

5. The button-raceway, the carrier having pockets, and the transerrer, combined with the slotted guideway having the driver-passage, and with a driver, a button raceway or 40 bar, and staple-detaining finger, substantially as described.

6. The slotted guideway having the driver-passage, the communicating staple raceway or 45 bar, and the transerrer to place a button with its shank open vertically in the driver-passage, combined with the anvil, the holder-guide g , and driver h , to drive the staple from the holder-guide, substantially as described. 50

7. A button-hopper, a button chute or raceway, a carrier to take buttons therefrom, a guideway grooved for the passage of a staple and driver and slotted at 2, the staple-hopper, staple raceway or bar, and staple-detaining finger at the end of the said staple raceway or bar, combined with a transerrer and with a driver to pass the staple into the eye of the button-shank, substantially as described. 55

In testimony whereof I have signed my name 60 to this specification in the presence of two subscribing witnesses.

JOHN H. VINTON.
